UNITED STATES PATENT OFFICE.

GUSTAV EGLOFF, OF CHICAGO, ILLINOIS.

PROCESS OF TREATING OIL.

Application filed April 26, 1917, Serial No. 164,618. Renewed September 27, 1922. Serial No. 591,003.

To all whom it may concern:

Be it known that I, GUSTAV EGLOFF, a citizen of the United States, residing in the city of Chicago, county of Cook, and State of Illinois, have invented certain new and useful Improvements in Processes of Treating Oils, of which the following is a specification.

This invention relates to improvements in process of treating hydrocarbon oils and refers more particularly to a cracking process by which relatively heavy hydrocarbons are converted into lighter boiling point hydrocarbons of either the saturated, unsaturated or aromatic series.

The salient object of the invention is to accomplish this cracking operation to provide new hydrocarbons of the character desired by means of the use of an electric arc seated in the body of the oil in the still and in direct contact therewith. The process is carried out either under a vacuum, atmospheric pressure or at pressure in excess of atmospheric depending upon the character of the low boiling point hydrocarbons which it is desired to produce.

Where the process is operated under a vacuum, a suitable suction or vacuum pump is preferably connected to the delivery side 30 of the receiving tank. When operating under pressure, this pressure may be produced either by means of a pump or by throttling the outlet side of the condensing system. The still, condenser and receiving tank are 35 all in free communication with each other. Preferably a duplex condenser which may take the form of an aerial condenser is interposed between the still and a water or similar condenser. The electrodes which 40 may be carbon points are suitably mounted in the still and connected to a suitable motor generator set.

To more clearly illustrate the invention, I have shown a drawing in which Fig. 1 is 45 a diagrammatic side elevation or view of the apparatus and Fig. 2 is a cross sectional view, and in which 1 designates the furnace, in which is mounted a still 2, which may be of the horizontal boiler type, or if desired 50 may take the form of a water tube boiler type. The still 2 is provided with a goose-neck 3 leading to an aerial condenser 4. This condenser, which takes the form of an inclined pipe is connected by branch 5 to 55 a condenser coil 6, mounted in condenser

boxes 7. The condenser box is supplied with cooling medium in a well known manner. The coil 6 is connected by pipe 8 through the receiving tank 9. To the upper end of the receiving tank 9 is connected a pump 10, by 60 means of pipe 11. A gas outlet 12 leads from the upper end of the tank and is controlled by valve 13. Draw off pipe 14 is connected to the bottom of the tank and is similarly controlled by a throttle valve 15. 65 A valve 16 is interposed in the pipe 11, so that the pump can be cut out of the system if desired. The water condenser coil 6 can be by-passed by means of pipe 17, leading to the pipe 4 through connection 18. Valves 70 19 and 20 are interposed in the pipe 17 and the branch pipe 5 can be closed by means of valve 21. The pump is so constructed that it may operate either as a vacuum pump or as a compressor pump. 75 When it operates as a compressor pump, the valve 16 is closed and the valves 19 and 20 may be opened and the pump pressure maintained on the system, or the valve 16 may be opened and the valves 19 and 20 80 closed and the pressure pump operate direct on the receiving tank. When it is desired to operate the pump as a vacuum, the bypass is preferably cut out of the system. If it is desired to distill and condense under 85 the pressure of the generated vapors alone, the valves 16 and 19 are closed and the pressure regulated by the throttle valves 13 and 15. If desired, a valve 22 is interposed between the outlet side of the water condenser 90 and the receiving tank 9. It is to be understood that the still and receiving tanks are equipped with suitable pressure gauges, safety valves, pyrometers, etc., all in a well 95 known manner.

The hydrocarbon oil is subjected to the action of the electric arc by closing a circuit through the electrodes 23 and 24, which may be carbon electrodes. Circuit through the electrodes is from the motor generator set 25, rheostat 26, ammeter 27, voltmeter 28, copper lead 29, through electrode 24, thence to electrode 23 to conductor 30, then through copper lead 31 and back to the motor generator set.

In operating the process, the oil is charged in the still, which may be crude petroleum oil, petroleum distillates, petroleum residues or other hydrocarbon oil. The motor generator set is then operated producing an arc 110

in the body of the oil. The distance of the arc is mechanically controlled, the electrodes being mechanically adjusted relative to each other, in a well known manner. The oil 5 may be preheated prior to the operation of the motor generator set, if desired, and may also be externally heated during the carrying out of the process. When it is desirous of forming unsaturated hydrocarbons such 10 as ethylene, propylene, and acetylene, which may be chlorinated for use as solvents for gums and the like, the cracking operation takes place in a vacuum. At low temperature and pressure gasoline and some benzine 15 are formed, but increasing the temperature at the same pressure causes the formation of benzene hydrocarbons but not abundantly. An increase of pressure increases the benzine hydrocarbon formation at high 20 temperatures, in other words, an increase of pressure increases low boiling point hydrocarbons of the saturated paraffine series and aromatic hydrocarbons of the benzene series at temperatures roughly, 400 C. to 25 500 C. But with an increase of temperature at the same pressure the benzene hydrocarbons form more rapidly at the expense of the paraffine hydrocarbons. When it is desired to form saturated hydrocarbons such 30 as gasoline or the benzine series, the process is operated under pressure in the manner heretofore described. This pressure may range from substantially atmospheric pressure to 200 pounds to the square inch or 35 more. If desired, fresh oil may be continuously fed into the still, thus making the process a continuous one. The temperature to which the oil should be heated will, of course, vary with the product desired and 40 the character of the oil being treated, but

it will, however, be treated sufficient to distill it.

The following is a typical run made under a pressure of 85 pounds upon a gas oil of 36° Baumé gravity obtained from an eastern 45 crude oil. I produced 50% pressure distillate of 53° Baumé gravity. This pressure distillate contained 63% of gasoline of 58.5 gravity or 31.5% of gasoline on the basis of gas oil used. 50

I claim as my invention:

1. A process of converting relatively high boiling point hydrocarbons into lower boiling point hydrocarbons, consisting in externally heating a bulk supply of oil and in simultaneously producing an electric arc within the body of said bulk supply of oil to heat the oil to a cracking temperature, in passing the evolved vapors through an aerial condenser from which reflux condensate returns to the bulk supply of oil, thence to a condenser and a receiver and in maintaining said bulk supply of oil under a selfgenerated superatmosphere vapor pressure. 60

2. A process of converting heavy hydrocarbons into lower boiling point hydrocarbons to produce a substantial percentage of liquid motor fuel, consisting in continuously externally heating the bulk supply of oil and in simultaneously producing an electric arc between electrodes emersed in said bulk supply of oil to raise the oil to a conversion temperature, in passing the evolved vapors to a condenser and in collecting the resulting distillate, and in maintaining a superatmospheric selfgenerated vapor pressure on the oil undergoing conversion. 70 75

GUSTAV EGLOFF.
